UNITED STATES PATENT OFFICE.

EDWARD A. TOLGEN, OF MINOT, NORTH DAKOTA.

RAIL-JOINT.

1,020,525.

Specification of Letters Patent. Patented Mar. 19, 1912.

Application filed July 6, 1911. Serial No. 637,142.

To all whom it may concern:

Be it known that I, EDWARD A. TOLGEN, citizen of the United States, residing at Minot, in the county of Ward and State of 5 North Dakota, have invented certain new and useful Improvements in Rail-Joints, of which the following is a specification.

The present invention comprehends certain new and useful improvements in rail 10 joints, and the object of the invention is to unite the meeting ends of companion rail sections in a particularly simple and reliable manner without the use of bolts or like fastening devices, thereby obviating the necessity of employing track walkers to inspect 15 and tighten the bolts from time to time and hence effecting a material economy in the cost of maintenance of the track.

Another object of the invention is to provide an improved chair which may be readily applied to the meeting ends of the rail sections and which serves both to thoroughly brace the sections against lateral strains and to rigidly support the sections to insure 25 against any sagging at the joint, the rail sections being positively confined in the chair but being free to move longitudinally therein to compensate for expansion and contraction.

30 A further object of the invention is to provide a joint which is quite strong and durable and which affords a practically continuous tread surface in order to prevent excessive wear on the ends of the rail sections 35 and eliminate the disagreeable and injurious pounding of the wheels of the rolling stock as they pass over the joint.

With these and other objects in view as will more fully appear as the description 40 proceeds, the invention consists of certain constructions, arrangements and combinations of the parts that I shall hereinafter fully describe and claim.

For a full understanding of the invention, 45 reference is to be had to the following description and accompanying drawing in which:

Figure 1 is a sectional perspective view of 50 a rail joint constructed in accordance with my invention; Fig. 2 is a transverse section; Fig. 3 is a detail perspective view of the meeting end of one of the companion rail sections; Fig. 4 is a fragmentary perspective view of the chair; and Fig. 5 is a bottom 55 plan view thereof.

Corresponding and like parts are referred

to in the following description and indicated in all the views of the accompanying drawing by the same reference characters.

The present invention includes a pair of 60 companion rail sections 1, each of which is of conventional form, except as hereinafter noted, and comprises a head 2, web 3 and base flange 4. At the meeting ends of the rail sections the webs are thickened, as indicated at 5, flush with both sides of the heads, so that said ends of the rail sections are substantially of uniform thickness from their tread surfaces to their base flanges. On each side of and coextensive with the 70 thickened webs, the base flanges are thickened and have their upper faces approximately perpendicular to the outer faces of the thickened webs to constitute upwardly facing square shoulders 6. However, it is 75 to be noted that the webs and base flanges are not thickened throughout the length of the rail sections but only for a predetermined distance from the ends, said parts being reduced in thickness intermediate of the ends 80 of the rail sections and the upper faces of the base flanges being inclined outwardly and downwardly, instead of being square, to enable spikes engaging over their edges to be driven well down into the cross-ties. 85 The extremities of the thickened ends of the rail sections are formed with recesses 7 on opposite sides of the rail, each recess extending the full height of the rail and half way across the same and providing a longitudinally projecting tongue 8 and a square shoulder 9 at the inner end of the tongue. 90 The inner faces of the tongues lie in vertical planes and abut against each other with the tongues in overlapping relation, the extremity of one tongue being adapted to bear against the shoulder at the inner end of the other tongue. This forms a scarf joint between the rail sections and thereby affords a practically continuous tread surface, 100 which, is of course, quite advantageous as it insures against undue wear on the ends of the rail sections and eliminates the disagreeable and injurious pounding of the wheels of the rolling stock as they pass over the joint. 105

The thickened ends of the rail sections are coupled together through the medium of a chair comprising a base plate 10 and a pair of longitudinal cheeks 11 upstanding from the base plate in transversely spaced relation, the rail sections resting upon the base plate between the cheeks with the joint lo-

cated midway between the ends of the chair. The base plate provides a rigid support for the rail sections for a considerable distance on both sides of the joint, so that the liability 5 of the rails sagging at the joint is effectually precluded. The cheeks are formed in their inner faces, just above their juncture with the base plate with longitudinal grooves 12 which are square in cross section and receive 10 the thickened portions of the base flanges of the rail sections, the upper portions of the cheeks overhanging the grooves and providing downwardly facing shoulders that bear evenly upon the upwardly facing shoulders 15 6 for the purpose of resisting any upward movement of the rail sections in the chair. The grooves extend throughout the entire length of the chair and open outwardly through the ends of the cheeks. Above the 20 grooves the inner faces of the cheeks are approximately vertical and bear snugly against the outer faces of the thickened web portions 5, whereby to confine the rail sections in alinement and to brace the same 25 against lateral strains. Preferably the cheek on the outer side of the rail is of greater height than the other cheek, as it thus obtains a more effective bearing on the rail sections to guard against side thrust and any 30 possible lateral tilting movement of the rail at curves in the track. The outer faces of the cheeks are rounded to slope downwardly and outwardly to shed rain water and other 35 foreign matter accumulating thereon.

35 While the chair fits around the rail sections to confine the same in alinement, it is in nowise positively secured thereto as it has been found desirable to leave the rails free to move longitudinally in the chair to compensate for expansion and contraction. By 40 avoiding the use of bolts or like fastening devices there is no danger of unduly weakening the rail sections, and furthermore it becomes unnecessary to employ track walkers to inspect the bolts and tighten the same from time to time. As a result a material 45 economy is effected in both the initial cost of the track and the cost of maintenance thereof. As best seen in Fig. 5 one or more 50 outlet openings 13 are formed in the base plate 10 below the scarf joint to provide means of escape for foreign matter collecting between the ends of the rail sections when the same are spaced apart within the 55 chair. Without these outlet openings rain water and the like would stand in the chair and would thus cause the sections to rust and would otherwise injure the parts and hinder the free longitudinal movement of 60 the rail sections in the chair.

The base plate projects laterally outwardly beyond the cheeks 11 to constitute attaching flanges 14 the outer edges of which are notched, as indicated at 15, to receive spikes 16 that attach the chair to one

or more cross-ties 17. In the present instance the chair rests on three cross ties in order to have a firm support, the upper faces of the ties being recessed as indicated at 18 to provide seats for the chair and to 70 compensate for the thickness of the base plate 10. The attaching flanges increase the width of the base plate, whereby to afford a broader bearing on the cross ties to increase the stability of the joint. 75

From the foregoing description in connection with the accompanying drawing, it will be seen that I have provided a joint which is quite simple and durable and consists of comparatively few parts. To assemble the parts it is merely necessary to slip the chair longitudinally on the meeting end of one rail section so that it is entirely positioned on such rail section and does not project longitudinally therebeyond. The 80 meeting ends of the two rail sections are then associated, after which the chair is slipped longitudinally to span the joint and is spiked to the cross-ties so as to be securely held against accidental displacement. It will be apparent, therefore, that the track may be laid with considerably less labor than is required where the rail sections are bolted together in the usual manner. The 85 joint also possesses great strength and solidity on account of the fact that the ends of the rail sections which fit within the chair, are thickened. 90

What I claim is:

1. In a rail joint, the combination with a pair of companion rail sections having their webs thickened at their meeting ends flush with both sides of their heads, and also having their base flanges thickened coextensive to said thickened webs to provide upwardly facing square shoulders, of a chair comprising a base plate supporting the meeting ends of the rail sections, and co-acting cheeks upstanding from the base plate and overhanging the square shoulders and abutting against the faces of the thickened webs. 100

2. In a rail joint, the combination with a pair of companion rail sections having their webs thickened at their meeting ends flush with both sides of their heads, and also having their base flanges thickened coextensive to said thickened webs to provide upwardly facing square shoulders, of a chair comprising a base plate supporting the meeting ends of the rail sections, and coacting cheeks upstanding from the base plate and overhanging the square shoulders and abutting against the faces of the thickened webs, the cheek on one side of the rail being extended upwardly above the other cheek to obtain a broad bearing on the rail sections, as and for the purpose specified. 105

3. In a rail joint, the combination of a pair of companion rail sections having their webs thickened at their meeting ends flush 115

120

130

with both sides of their heads, and also having their base flanges thickened on each side of said thickened webs to provide upwardly facing square shoulders, the thickened ends 5 of the rail sections being recessed on opposite sides of the rail to provide mating longitudinal tongues overlapping to form a scarf joint, of a chair comprising a base plate supporting the meeting ends of the 10 rail sections, and coacting cheeks upstanding from the base plate and formed in their inner faces with longitudinal grooves receiv-

ing said thickened portions of the base flanges, the upper portions of the cheeks overhanging the grooves and bearing upon 15 the upwardly facing square shoulders and also abutting against the faces of the thickened webs.

In testimony whereof, I affix my signature in presence of two witnesses.

EDWARD A. TOLGEN. [L. s.]
